LASTING MACHINE

Michele Cuozzo, Lynn, Mass.

Application May 7, 1949, Serial No. 91,919

27 Claims. (Cl. 12—8.3)

1

This invention pertains to shoe lasting machines of the continuous or progressive type wherein the lasting margin of the upper is gripped between opposed parts, one at least of which is a constantly rotating roll, while it is subjected to the lasting stress. One object of the present invention is to provide a lasting machine of the continuous type which is capable of applying a more powerful updrafting stress than it is possible to obtain by the use of some of the prior machines of this type. A further object is to provide a lasting machine of the continuous type wherein the degree of updrafting stress may be varied during the lasting operation at the will of the operator. A further object is to provide a lasting machine of the continuous type having means whereby a substantially uniform lasting stress may be applied to the lasting margin. A further object is to provide a lasting machine of the continuous type having provision for roughening the exposed surface of the lasting margin as it is wiped in over the shoe bottom. A further object is to provide a lasting machine comprising a minimum number of parts; which is of simple and inexpensive construction; which is of small dimensions and light in weight; and which is rugged, durable and easy to operate. Other and further objects and advantages of the invention will be pointed out in the following more detailed description and by reference to the accompanying drawings wherein:

Fig. 1 is a side elevation of a lasting machine in accordance with one embodiment of the invention;

Fig. 2 is a fragmentary horizontal section, to larger scale, substantially on the line 2—2 of Fig. 1;

Fig. 3 is a front elevation, viewed from the left-hand side of Fig. 1, of the upper gripping and wiping means, the other parts being omitted;

Fig. 4 is a fragmentary side elevation similar to Fig. 1 but showing the rear end only of the machine and illustrating a slight modification;

Fig. 5 is a view similar to Fig. 4, showing a further modification;

Fig. 6 is a fragmentary section on the same plane as Fig. 2 but illustrating a slight modification, wherein provision is made for roughening the lasting margin;

Fig. 7 is an elevation, looking from the left-hand side of Fig. 6;

Fig. 8 is a plan view of the device shown in Fig. 7;

Fig. 9 is a diagrammatic vertical section, substantially in the plane of line 9—9 of Fig. 1, but

to larger scale, showing the relation of the wiping elements to the lasting margin of the shoe during the lasting operation;

Fig. 10 is a fragmentary section on the line 10—10 of Fig. 2, omitting the work-gripping elements and showing the support for the inner work-gripping roll;

Fig. 11 is a diagrammatic front elevation showing a shoe in the position in which it is held during the lasting operation;

Fig. 12 is a diagrammatic plan view of the parts shown in Fig. 11 and illustrating the action of the machine in stressing the upper material;

Fig. 13 is a fragmentary horizontal section showing a slight modification;

Fig. 14 is a view similar to Fig. 6, illustrating a modified form of wiper; and

Fig. 15 is a view similar to Fig. 14 but showing another modification.

20 Referring to the drawings, the numeral 1 designates a bench, or other suitable support, upon which the frame of the machine may be mounted. As shown in Fig. 1, the frame of the machine comprises a base 2 from which rises the upright post or column 3, carrying the lower member 4 of a bearing which also comprises the upper or cap member 5 secured to the part 4 by bolts or the like. This bearing, comprising the parts 4 and 5, houses a sleeve or bushing 6 (Fig. 2) within which turns the horizontal tubular shaft 7. As illustrated in Fig. 2, the left-hand end of the shaft 7 projects beyond the bearing and is received in an axial bore in an elongate hub 9 which is keyed, as indicated at 10, to the shaft 7, or otherwise fixed to the shaft. Alternatively, the shaft 7 and hub 9 may be integrally joined. At its left-hand end the part 9 has a radial flange 12 and a centrally located chamber 11. The flange 12 has an annular internal channel 13 communicating with the chamber 11 and in this channel is seated an annular internal bevel gear 14, the gear being fixedly secured to the part 12 in any suitable manner, for example by pins or by welding.

45 The shaft 7 (Fig. 1) projects to the right beyond the bearing comprising the parts 4 and 5 and to this portion of the shaft there is fixed the hub 16 of a drive pulley 17, designed to receive a belt driven, for example, by an electrical motor (not shown).

The bore in the shaft 7 is provided with a lining sleeve or bushing 18 (Fig. 2) in which is arranged an axially slidable shaft or rod 19. This rod 19 projects to the right (Fig. 1) beyond the pulley 17 and slides in bearings 20 and 21

3

provided by a U-shaped frame member 22 which is secured to the bench or table 1. If desired, the parts 2 and 22 may be integrally joined. Moreover, if desired, these parts 2 and 22, whether separate or integral, may be mounted upon a suitable base or column, forming a part of the machine structure itself.

Any suitable means may be provided to prevent rotation of the shaft 19, but, as here illustrated, merely by way of example, the right-hand end of the shaft is provided with a collar 23 secured to the shaft by a set screw, or the like, and having a rigid pin 24 which extends through and is slideable in an opening in the frame member 22. With this arrangement, by loosening the collar 23, it is possible to turn the shaft 19 by hand for adjusting its angular position. However, the shaft 19 is normally held against rotation, although it may slide axially relatively to the shaft 7.

A spring 24 surrounds the shaft 19, bearing at one end against the part 22 and at its other against a collar 25 which is pinned to the shaft 19 and which has a peripheral groove which receives opposed pins 26 projecting from a forked arm 27 of a bell-crank lever pivoted at 28 in a bracket 29 projecting from the part 22. This bell-crank has another arm 30 which is connected by a rod 31 to and other suitable connections (not shown) to a treadle. The spring 24 normally urges the rod 19 rearwardly with a force depending upon the strength of the spring 24, but by actuation of the treadle, the rod 19 may be moved forwardly relatively to the shaft 7.

The shaft or rod 19 projects into the chamber 11 (Fig. 2), as indicated at 19a, and is provided at its left-hand end with a fixed stub shaft or pin 32 (Fig. 10) whose axis makes an acute angle G, 32 (Fig. 10) whose axis makes an acute angle G, which may for example be approximately 45°, with the axis of the rod 19. This stub shaft or pin 32 may be secured to the shaft 19 in any suitable manner, for example, by a screw-thread connection, by welding, or the like, and its free end is provided with a button 33 preferably having a spherically curved outer surface which is designed to engage the shoe bottom (usually the insole) and to act as a hold-down or limiting element to oppose the updraft which is applied to the lasting margin of the upper.

The stub shaft 32 (Fig. 2) is provided with a bearing bushing 34 of suitable material, for example, bronze, and on this bushing turns the hub 35 of a beveled pinion 36, of such pitch that its teeth may mesh with the teeth of the internal bevel gear 14, the pitch angle being approximately the same as the angle G above referred to. The diameter of the pinion, as here shown, is approximately one-half that of the annular gear 14. The head or button 33 on the stub shaft retains this pinion in proper operative position on shaft 32.

Preferably, the outer radial face of the flange member 12 is provided with a series of projecting bosses 37 (Fig. 3), here shown as substantially hemispherical, and which form the heads of pins 37a (Fig. 2) which extend through openings in the flange 12 and are fixed therein, for example by screw threading, welding or the like.

The operation of the machine (Figs. 2, 11, 12 and 13), as thus far described, is substantially as follows, assuming that a shoe upper U, having a lasting margin M, has been assembled with an insole S upon the last L and that the pulley 17 is being driven from a suitable source of power. The operator first depresses the treadle, thereby pushing the rod 19 forwardly so as to separate the

teeth of the pinion 36 from the teeth of the gear 14. He then presents the shoe (Fig. 13) to the machine so that the insole contacts the curved surface of the button 33 and introduces the lasting margin between the toothed rolls 14 and 36. He then removes his foot from the treadle, allowing the spring 24 to urge the rod 19 and the pinion 36 rearwardly. The internal gear 14 now grips the lasting margin between it and the pinion 36 and, as the gear 14 turns, the rotary parts 14 and 36 exert a force substantially in the axial direction, as referred to the shaft 19, which produces a powerful updrafting effect on the lasting margin, drawing it snugly about the last. The strong tension exerted on the upper material by the toothed rolls 14 and 36 is clearly evident by visual observation of the upper material at the point P (Fig. 12), the effect apparently being somewhat similar to that obtained by the hand laster when he seizes the upper with hand pincers and applies twisting force to the pincer handles. During the lasting operation the lasting margin is drawn or wrapped about the periphery of the pinion 36 by the action of the internal gear 14, and subjected to a very strong pull such that the upper is drawn into a deep wrinkle P, indicative of the powerful stress which is applied. At the same time, the shoe is fed forwardly by the action of the rotating pinion and gear. As the lasting margin, after being stressed by the interaction of the gear and pinion, escapes from between the gear and pinion at the point E (Figs. 11 and 12), it is engaged by the bosses 37 on the downwardly moving portion of the flange 12 and, before it can retract, is wiped in over the bottom of the insole. Assuming that adhesive has been applied, either to the lasting margin or the insole, or both, this operation wipes in and causes the lasting margin to adhere firmly to the insole. The operation is continued throughout such portions of the periphery of the shoe as are to be lasted by this particular machine. This may include the entire periphery of the shoe, the forepart and toe portions only, or only the parts comprised in what is known as the "side lasting" operation.

Instead of the rounded bosses 37 on the flange 12, an arrangement such as shown in Figs. 6 to 8 may be employed. In this arrangement, the part 90 corresponds to the part 9, previously described, and the part 120 to the flange 12, previously described. However, in this instance, the left-hand face of the flange 120 is formed by an independent ring 121 secured in place by screws 122 and having on its exposed radial face a series of teeth 123 designed, as they engage the lasting margin, during the wiping operation, to abrade or roughen its surface so as to prepare it for the reception of cement for use in attaching the outer sole.

In a similar way (Fig. 14), instead of the ring 121, with its roughing teeth 123, a ring 131 carrying rotatable ball bearings 133 may be secured to the flange 120, thus providing somewhat the same effect as the bosses 37, but causing less roughing or injury to the surface of the lasting margin.

Instead of having the spring 24 arranged to exert a rearward force for drawing the pinion 36 toward the gear, the reverse arrangement may be employed, as shown in Fig. 5, wherein the spring 124 is arranged to urge the shaft 19 forwardly so as to separate the pinion and gear. In this case, the pinion is moved toward the gear by the action of the treadle so that the operator may determine the pressure between the gear and

pinion and thus vary the degree of stretch imparted to the lasting margin.

A further alternative is illustrated in Fig. 4 wherein the spring is arranged to urge the rod 19 forwardly so as to separate the pinion and gear, but with no provision for moving the pinion toward the gear, except by the pressure of the work against the button 33.

The rolls 14 and 36 may, as here illustrated, be actual gears such as are used in power transmission. However, the teeth need not be of the exact shape requisite in true gear teeth, but may merely be ribs of any desired shape such as to provide a good grip; and even rolls, whether or not provided with knurled peripheral surfaces, if complementally beveled and relatively arranged like the rolls 14 and 36, are also capable of giving good results, at least upon some classes of work, and when the parts 14 and 36 are here referred to for convenience as gears, the term "gear" is to be considered as inclusive of variations, as just suggested by way of example.

In Fig. 13 a slight modification is shown wherein the axis of the pinion 36 is parallel with but eccentric to the axis of the gear 14.

In Fig. 15 a further modification is illustrated wherein the flange 12 of the part 9 is provided with circumferentially spaced sockets 140 which house coiled compression springs 141 whose forward ends engage the inner faces of sliding plugs 142 having spherically curved outer ends 143 which function like the parts 37 and 133, above referred to.

While desirable embodiments of the invention have herein been illustrated and described by way of example and certain modifications suggested, it is to be understood that the invention is broadly inclusive of any and all further modifications and rearrangements of parts which fall within the terms of the appended claims.

I claim:

1. In combination in a lasting machine, a support, a hold-down device carried by the support, a rotatable roll mounted on the support, said roll having a beveled peripheral surface, wiping means movable in a plane which intersects the axis of the roll at an acute angle, means operative partially to wrap the lasting margin of a shoe upper about the beveled surface of the roll while uninterruptedly advancing the work, and means operative simultaneously to actuate the wiping means and the wrapping means.

2. In combination in a lasting machine, a support, a hold-down device carried by the support, a rotatable roll mounted on the support, said roll having a beveled peripheral surface, wiping means movable in a circular path lying in a plane which intersects the axis of the roll at an acute angle, a rotatable annulus coaxial with the path of the wiping means, constructed and arranged to grip a lasting margin between it and the roll, and concomitantly to feed the work along, and means operative simultaneously to rotate the annulus and to move the wiping means.

3. In combination in a lasting machine, a support, a hold-down device carried by the support, a rotatable roll mounted on the support, said roll having a beveled peripheral surface, wiping means movable in a circular path lying in a plane which intersects the axis of the roll at an acute angle and a rotatable annulus coaxial with the path of the wiping means, said annulus having a beveled inner surface provided with work-engaging ribs, said annulus being operative to grip a lasting margin between its beveled surface and

that of the roll, thereby to create updrafting stress while concomitantly advancing the work, and means operative simultaneously to rotate the annulus and the wiping means.

5. Shoe lasting apparatus for updrafting and inwiping the lasting margin of a shoe upper, said apparatus comprising an annulus and means for rotating it, said annulus having a toothed surface at its inner periphery, an abutment element 10 arranged within the annulus, the abutment element being eccentrically located relatively to the annulus and being bodily movable in a direction parallel to the axis of the annulus, thereby to permit the entry of the lasting margin of the 15 shoe upper between the abutment and the toothed surface of the annulus, and wiper elements carried by the annulus operative to wipe the lasting margin inwardly as the margin escapes from between the annulus and abutment.

20 6. Shoe lasting apparatus for updrafting and inwiping the lasting margin of a shoe upper, said apparatus comprising an annulus and means for rotating it, said annulus having a toothed surface at its inner periphery, an abutment element 25 arranged within the annulus, the abutment element being eccentrically located relatively to the annulus and being bodily movable relatively to the annulus away from the toothed surface of the annulus thereby to permit the entry of the 30 lasting margin of the shoe upper between the abutment and the toothed surface of the annulus, and means carried by the annulus operative to wipe in and to roughen the lasting margin as the latter escapes from between the abutment and annulus.

35 6. Shoe lasting apparatus for updrafting and inwiping the lasting margin of a shoe upper, said apparatus comprising an annulus and means for rotating it, said annulus having a toothed surface at its inner periphery, an abutment element 40 arranged within the annulus, the abutment element being eccentrically located relatively to the annulus and being bodily movable relatively to the annulus away from the toothed surface of the 45 annulus thereby to permit the entry of the lasting margin of the shoe upper between the abutment and the toothed surface of the annulus, a ring removably secured to the forward face of the annulus, and wiper elements carried by the ring.

50 7. Shoe lasting apparatus for updrafting and inwiping the lasting margin of a shoe upper, said apparatus comprising an annulus and means for rotating it, said annulus having a toothed surface at its inner periphery, an abutment element 55 arranged within the annulus, the abutment element being eccentrically located relatively to the annulus and being bodily movable relatively to the annulus in a direction parallel to the axis of the annulus thereby to permit the entry of the 60 lasting margin of the shoe upper between the abutment and the toothed surface of the annulus, a ring removably secured to the forward face of the annulus, and work-roughening elements carried by the ring.

65 8. Shoe lasting apparatus for updrafting and inwiping the lasting margin of a shoe upper, said apparatus comprising a rotary carrier, an internal bevel gear mounted on the carrier, means for rotating the carrier, a beveled pinion of a diameter approximately one-half that of the gear, arranged within the gear, a normally fixed shaft supporting the pinion, a hold-down element carried by said shaft and engageable with the shoe bottom, and wiper elements mounted on the carrier.

9. Shoe lasting apparatus for updrafting and inwiping the lasting margin of a shoe upper, said apparatus comprising a rotary carrier, an internal bevel gear mounted on the carrier, means for rotating the carrier, a beveled pinion, of a diameter approximately one-half that of the gear, arranged within the gear, a normally fixed shaft supporting the pinion, a hold-down element carried by said shaft and engageable with the shoe bottom, and combined wiping and roughening elements mounted on the carrier.

10. Shoe lasting apparatus for updrafting and inwiping the lasting margin of a shoe upper, said apparatus comprising a rotary carrier, an internally ribbed annulus mounted on the carrier, means for rotating the carrier, a beveled toothed roll, of a diameter approximately one-half that of the annulus, arranged within the annulus, a normally fixed shaft supporting the roll, a hold-down element supported by said shaft and engageable with the shoe bottom, and a series of smoothly rounded knobs projecting from the carrier and constituting wiping elements.

11. Shoe lasting apparatus for updrafting and inwiping the lasting margin of a shoe upper, said apparatus comprising a rotary carrier, an internally beveled annulus mounted on the carrier, means for rotating the carrier, a beveled roll, of a diameter approximately one-half that of the annulus, arranged within the annulus, a normally fixed shaft supporting the roll, a hold-down element supported by said shaft and engageable with the shoe bottom, and a series of work-roughening teeth projecting from the carrier and operative to wipe in and roughen the marginal material.

12. In a shoe lasting machine, in combination, a frame, and means supported thereby for gripping and updrafting the lasting margin of a shoe upper, said gripping means comprising an annulus having a beveled inner peripheral surface, work-gripping elements on said surface, a rotary abutment disposed within said annulus and located eccentrically with relation to the annulus, said abutment having a beveled peripheral surface complementary to the beveled surface of the annulus, the abutment being bodily movable toward the beveled surface of the annulus, thereby to grip the lasting margin between the beveled surfaces of the abutment and annulus, means for rotating the annulus, a hold-down device engageable with the shoe bottom to oppose stress exerted by the gripping means, a normally stationary element, carried by the frame, on which the hold-down device is mounted, and wiping means operative to engage and to wipe in the margin as it escapes from between the abutment and annulus.

13. In a shoe lasting machine, in combination, means for gripping and updrafting the lasting margin of a shoe upper, said gripping means comprising an annulus having a beveled inner peripheral surface, work-gripping elements on said surface, a normally stationary support arranged within the annulus, a shaft carried by the support, a rotary abutment roll free to turn on said shaft, said roll having a beveled peripheral surface complementary to that of the annulus, a hold-down element mounted on the end of said shaft and engageable with the shoe bottom to oppose the drafting stress exerted by the gripping elements, and wiping means carried by the annulus.

14. In a shoe lasting machine, in combination, means for gripping and updrafting the lasting margin of a shoe upper, said gripping means com-

prising an annulus having a beveled inner peripheral work gripping surface, an axially movable, normally stationary rod coaxial with the annulus, a stub shaft arranged within the annulus and supported by the rod, the axis of said shaft being inclined to the axis of the annulus at substantially the same angle that the beveled surface of the annulus makes with the axis of the latter, said stub shaft having a head at its forward end constituting a work hold-down, a freely rotatable roll mounted on the stub shaft, said roll having a beveled work-gripping face complementary to that of the annulus, means for rotating the annulus, and means mounted on the forward radial face of the annulus for wiping in the lasting margin as the latter escapes from between the beveled surfaces of the annulus and roll.

15. In a shoe lasting machine, in combination, means for gripping and updrafting the lasting margin of a shoe upper, said gripping means comprising an annulus having a beveled inner peripheral surface, an axially movable, normally nonrotatable rod coaxial with the annulus, a stub shaft fixed at one end to the forward end of the rod, the axis of the stub shaft being inclined relatively to the axis of the annulus, a hold-down device carried by said stub shaft at its free end, a roll mounted on the stub shaft, said roll having a beveled peripheral face complementary to the beveled face of the annulus, each of said beveled faces having work-gripping ribs, means for rotating the annulus, means for moving the rod axially, thereby to urge the beveled face of the roll toward that of the annulus, and a series of projections on the forward radial face of the annulus operative to engage and to wipe in the lasting margin as the latter escapes from between the gripping elements.

16. In a shoe lasting machine, in combination, means for gripping and updrafting the lasting margin of a shoe upper, said gripping means comprising an annulus having a beveled inner peripheral work-gripping surface, an axially movable, normally nonrotatable rod coaxial with the annulus, a stub shaft fixed at one end to the forward end of the rod, the axis of the stub shaft being inclined relatively to the axis of the annulus, a hold-down device carried by said stub shaft at its free end, a roll mounted on the stub shaft, said roll having a beveled peripheral work-gripping face complementary to the beveled face of the annulus, said beveled faces gripping the work between them, means for rotating the annulus, a spring which constantly tends to move said rod in one direction, manually actuatable means for moving the rod in the opposite direction, and wiping means carried by the annulus.

17. In a shoe lasting machine, in combination, means for gripping and updrafting the lasting margin of a shoe upper, said gripping means comprising an annulus having a beveled inner peripheral surface, an axially movable, normally nonrotatable rod coaxial with the annulus, a stub shaft fixed at one end to the forward end of the rod, the axis of the stub shaft being inclined relatively to the axis of the annulus, a hold-down device carried by said stub shaft at its free end, a roll mounted on the stub shaft, said roll having a beveled peripheral face complementary to the beveled face of the annulus, each of said beveled faces having work-gripping ribs, means for rotating the annulus, a spring which constantly tends to move the rod rearwardly, thereby to urge the beveled face of the roll toward the beveled face of the annulus, treadle-actuated

means for moving the rod forwardly, thereby to separate the roll and annulus, and a series of work engaging projections on the forward radial face of the annulus.

18. In a shoe lasting machine, in combination, means for gripping and updrafting the lasting margin of a shoe upper, said gripping means comprising an annulus having a beveled inner peripheral surface, an axially movable, normally nonrotatable rod coaxial with the annulus, a stub shaft fixed at one end to the forward end of the rod, the axis of the stub shaft being inclined relatively to the axis of the annulus, a hold-down device carried by said stub shaft at its free end, a roll mounted on the stub shaft, said roll having a beveled peripheral face complementary to the beveled face of the annulus, each of said beveled faces having thereon work-gripping elements, means for rotating the annulus, a spring which constantly tends to move the rod forwardly, thereby to separate the beveled faces of the roll and annulus, means whereby the rod may be moved rearwardly, and wiper means carried by the annulus.

19. In a shoe lasting machine, in combination, means for gripping and updrafting the lasting margin of a shoe upper, said gripping means comprising an annulus having a beveled inner peripheral work-gripping surface, an axially movable, normally nonrotatable rod coaxial with the annulus, a stub shaft fixed at one end to the forward end of the rod, the axis of the stub shaft being inclined relatively to the axis of the annulus, a hold-down device carried by said stub shaft at its free end, a roll mounted on the stub shaft, said roll having a beveled peripheral work-gripping face complementary to the beveled face of the annulus, said beveled faces gripping the work between them, means for rotating the annulus, a spring which constantly tends to move the rod forwardly, thereby to separate the beveled face of the roll from that of the annulus, and treadle-actuated means for moving the rod rearwardly thereby to grip the lasting margin between the roll and annulus.

20. Shoe lasting apparatus including a frame, and upper stressing means carried thereby including a pair of normally meshing, toothed, upper gripping elements arranged to turn about axes which intersect at an acute angle, one of said elements being an internal beveled gear and the other being a beveled pinion, means for turning one, at least, of said elements, means for urging said elements toward each other, thereby to grip the lasting margin between their toothed faces, said gripping elements being operative to exert updrafting stress on the lasting margin gripped between them, limiting means operative, by engagement with the insole, to limit movement of the insole and last in the direction of said updrafting stress, and a normally stationary part carried by the frame constituting the support for said limiting means.

21. Shoe lasting apparatus comprising upper stretching and work-feeding means designed to grip the lasting margin of the shoe upper and concomitantly to exert updrafting stress and work-feeding stress, said stretching and feeding means comprising a pair of toothed, rotatable gripper elements capable of relative bodily movement to admit the lasting margin between them, means for relatively moving said elements toward each other, one of said elements being an internally beveled toothed annulus and the other a beveled toothed roll arranged within and in

eccentric relation to the annulus, means for turning the annulus, and wiping means movable in a path coaxial with the annulus.

22. Shoe lasting apparatus comprising upper stretching and work-feeding means designed to grip the lasting margin of the shoe upper and concomitantly to exert updrafting stress and work-feeding stress, said stretching and feeding means comprising a pair of work-gripping ele-

10 ments capable of relative bodily movement to admit the lasting margin between them, means for relatively moving the gripping elements toward each other, one at least of said elements being rotatable, a wiper element which is movable in a circular path coaxial with said rotary gripping element and means operative simultaneously to turn said rotary gripping element and the wiper element continuously in the same direction.

20 23. Shoe lasting apparatus comprising upper stretching and work-feeding means designed to grip the lasting margin of the shoe upper and concomitantly to exert updrafting stress and work-feeding stress, said stretching and feeding

25 means comprising a pair of work-gripping elements capable of relative bodily movement to admit the lasting margin between them, means for relatively moving the gripping elements toward each other, one at least of said elements

30 being rotatable, an annular wiper element coaxial with said rotary gripping element and whose path of movement is in a plane perpendicular to the axis of the said rotary gripping element and means operative simultaneously to turn said gripping element and the wiper element continuously in the same direction.

24. Shoe lasting apparatus comprising upper stretching and work-feeding means designed to grip the lasting margin of the shoe upper and

40 concomitantly to exert updrafting stress and work-feeding stress, said stretching and feeding means comprising a pair of rotatable elements capable of relative bodily movement to admit the lasting margin between them, said elements being 45 rotatable about axes which intersect at an angle of approximately 45°, means for rotating one at least of said elements continuously in the same direction, and wiping means movable in an annular path coaxial with one of said rotatable elements.

25. Shoe lasting apparatus comprising upper stretching and work-feeding means designed to grip the lasting margin of the shoe upper and concomitantly to exert updrafting stress and

55 work-feeding stress, said stretching and feeding means comprising a pair of rotatable gripper elements having opposed beveled faces, said elements being so supported that one may be moved away from the other to admit the lasting margin between them, means for moving them toward each other to grip the margin between them, a wiper element, and means for moving the wiper element in a path coaxial with one of said gripper elements.

60 26. In combination in a lasting machine of the continuous type comprising a pair of co-operable work-gripping elements of which one, at least, is rotatable, said elements being bodily separable to admit the lasting margin of the shoe upper between them, means for urging said elements relatively toward each other to grip the lasting margin between them, means operative to rotate at least one of said gripping elements, a wiper element which is movable in a closed path, the point at which the lasting margin is

11

gripped between the gripping elements being located within the confines of said path, and means operative simultaneously to turn the rotary gripping element and to move the wiper element always in the same direction along said path.

27. In combination in a lasting machine of the continuous type comprising a pair of co-operable work-gripping elements of which one, at least, is rotatable, said elements being bodily separable to admit the lasting margin of the shoe upper between them, means for urging said elements relatively toward each other to grip the lasting margin between them, means operative to rotate at least one of said gripping elements,

5

10

12

a wiper element movable in a circular path, the point at which the margin is gripped between the gripper elements being within and eccentrically located with respect to the path of the wiper element and means operative simultaneously to turn said rotary gripping element and to move the wiper element always in the same direction along said circular path.
